US00D994835S

(12) **United States Design Patent** (10) **Patent No.:** **US D994,835 S**
(45) **Date of Patent:** **** Aug. 8, 2023**

(54) **FILTER CASE FOR WATER PURIFICATION**

(71) Applicants: **Microfilter CO., LTD,**
Chungcheongbuk-do (KR); **HISENSE**
RONSHEN (GUANGDONG)
REFRIGERATOR CO., LTD.,
Guangdong (CN)

(72) Inventors: **Kyong Su Lee**, Hwaseong-si (KR); **Pil**
Kang Hwang, Jincheon-gun (KR); **Min**
Kyu Jung, Gumi-si (KR)

(73) Assignees: **Microfilter CO., LTD**, Jincheon-gun
(KR); **HISENSE RONSHEN**
(GUANGDONG) REFRIGERATOR
CO., LTD., Foshan (CN)

(**) Term: **15 Years**

(21) Appl. No.: **29/844,196**

(22) Filed: **Jun. 27, 2022**

Related U.S. Application Data

(63) Continuation-in-part of application No. 29/729,870,
filed on Mar. 31, 2020, now abandoned.

(57) **CLAIM**

We claim the ornamental design for the filter case for water purification, as shown and described.

DESCRIPTION

FIG. 1 is a perspective view of a filter case for water purification;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof; and,

FIG. 8 is an exploded view thereof.

The broken lines in the figures depict the unclaimed environment of the design.

1 Claim, 8 Drawing Sheets
